YORK, A CORPORATION OF NEW YORK.

COLLAR MOLDING AND FINISHING MACHINE.

1,214,196.

Specification of Letters Patent. Patented Jan. 30, 1917.

Application filed March 31, 1914. Serial No. 828,637.

To all whom it may concern:

Be it known that we, THOMAS W. LLEWELLYN and JAMES J. DOYLE, citizens of the United States, and residents of Syracuse, in the county of Onondaga and State of New York, have invented a certain new and useful Collar Molding and Finishing Machine, of which the following is a specification.

This invention has for its object a collar molding and finishing machine, which is particularly simple in construction, and highly efficient and rapid in its operation; and it consists in the combinations and constructions hereinafter set forth and claimed.

In describing this invention, reference is had to the accompanying drawings, in which like characters designate corresponding parts in all the views.

Figure 1 is a side elevation, partly in section, of our collar molding machine. Fig. 2 is a plan thereof. Figs. 3 and 4 are detail views.

This collar molding machine comprises, generally, two elements, one a head having an annular socket, and the other a ring for receiving the collar, the head and the ring having relative movement one toward and from the other for interfitting the ring with the collar thereon and the socket to mold the collar, one of the elements also having a rotative movement for ironing out the rough edges on the fold of the collar after the elements are brought into interfitting relation, and means for effecting the relative movements of said elements.

In the machine here illustrated, the head is stationary and the ring is movable into and out of registration with the head and toward and from the head, and also has a slight rotative movement.

1 is the head which is supported in any suitable manner by the frame 2, the head having an annular molding socket 3 in its lower side and also having a jacket which forms an internal annular chamber 4 around the socket and in which is located electrical resistance coils 5 which when connected in a circuit will heat the socket 3.

6 designates the ring which is carried by a suitable support or bed 7. This ring is provided with yielding sections 8—Figs. 2 and 3—separate from the main body of the ring and yieldingly mounted in the support or bed 7 and yieldable in a direction paral-

le to the axis of the ring. The yieldable sections are arranged to underlie the folds in the hems near the front ends of the collar, and the sections are depressible slightly below the edge of the greater portion of the ring so as to provide space for the extra thicknesses of the hems, and hence the hems will not be split or cracked during the molding operation. Usually a shield 9 of thin yielding metal covers the ring. The yieldable sections are seated upon strips 10 of yielding material as rubber. The yieldable sections form the subject matter of our pending application, Sr. No. 775,875, filed June 26, 1913.

We have here shown in this embodiment of our invention, two rings 6 supported by a carriage movable about an axis for carrying the rings into and out of alinement with the socket 3 of the head 1, the rings 6 and their carriage in this embodiment of our invention, also having movement toward and from the head and rotative movement in the head.

11 is the carriage rotatably mounted on an upright shaft 12 forming part of the frame 2 and having diametrically disposed upright bearings 13 on which the ring supports 7 are mounted, the bearings 13 being tubular and easily fitting bosses or hubs 14 at the centers of the ring supports. Each ring is secured to the corresponding arm of the carriage 11 by a spindle 15 extending coaxially of the bearing 13 and hub 14 and having a shoulder 16 near its lower end engaging the lower face of the carriage 11 and a nut 17 at its upper end overlying the end of the hub 14. Yielding means as a spring 18 is interposed between the ring support 7 and the carriage, the spring 18 encircling the spindle 15 and pressing at its upper end upwardly on the hub and being seated at its lower end on the carriage 11, an antifriction thrust bearing 19 being inserted between the upper end of the spring and the top of the hub within the hollow hub 14. The spring yields when the carriage 11 is lifted upwardly to carry the ring 6 into the socket 3 and after the collar on the ring engages the socket 3.

The carriage 11 is rotatable by hand and means is provided for stopping and centering the carriage when one of the rings 6 is alined with the head 1, said means consist

of spring pressed plungers or balls 20—Figs. 2 and 4—carried by the hub 21 of the carriage 11 and movable into vertical grooves 22 located on diametrically opposite sides of the shaft 12, the grooves being arranged so that the plungers 20 enter the same when one or the other of the rings 6 is alined with the socket 3.

The means for actuating the rings 6 toward and from the head 1 comprises a reciprocating carriage 23 on the shaft 12 and a similar shaft 12^a on the opposite side of the machine, the carriage being actuated upwardly by means of a cam 25 mounted on a rock shaft 26 journaled in suitable bearings on the frame and having an upwardly extending hand lever 27 by means of which said shaft is rocked. The cam 25 coacts with a roller 28 on the carriage 23.

The motion of the carriage 23 is transmitted to the ring support 7 through the spindle 15 and also by the bearing 24 on the shaft 12, which bearing engages the hub of the carriage 11. The hub of the carriage 11 and the lower end of the spindle 15 are normally spaced apart from the bearing 24 and the carriage 23, coacting therewith, and the spindle 15 is formed tapered at 29 and fits a tapered socket 30 in the carriage, the tapered point and socket tending to center the carriage during raising thereof.

The rotative movement of each ring 6 is here shown as effected during yielding movement of the spring 18 by a cam means provided on the ring support 7 and the bearing 13 of the carriage 11.

As here shown, each ring support is provided with a plurality of inclined cam slots 31 located in the hub thereof and extending at a slight incline relatively to the direction of movement of the ring 6 toward and from the head, and the bearing 13 is formed with shoulders or wipers 32 normally arranged at the bottoms of the slots and coacting with the inclined sides of the slots after the movement of the ring 6 with the carriage 11 is limited by the socket 3, the inclined sides of the slots passing along the wipers causing a slight rotative movement of the ring 6 and its support 7 during the compression of the spring 18.

In order to prevent slipping of the collar on the ring during its rotative movement, a grip is provided for engaging the collar during compression of the spring 18, that is, during the movement of the carriage 11 after the movement of the ring 6 has been limited.

33 designates the collar grip which is in the form of a spring clip fixed at its lower end at 34 to the ring support 7 and having its other end bent to engage the inner lap of the collar. The grip is operated by means movable with the carriage 11 as an arm 35 rising from the carriage and extending

through the ring support and engaging at its upper end with the inclined portion 36 on the grip 33.

The upper end of the arm 35 is normally spaced apart from the surface 36 of the grip 33 and moves into engagement therewith when the spring 18 begins to yield.

In our machine, the molding and rough edge removing operations are performed at the same time.

In operation, the operator places a collar on the ring which is out of registration with the head 1, turns the carriage 11 to move the ring with the collar thereon under the head 1, operates the hand lever 27 to cause the carriage 23 to lift the carriage 11 and carry the ring with the collar thereon into the head 1, and during the lifting operation the ring is given a rotative motion by reason of the slot 31 and the wiper 32.

Although we have shown and described one particular construction of collar molding machine and specific details of construction of the same, certain features of the invention are broader in scope than their relation particularly to collar molding machines and are adapted to be applied to ironing machines in general which embody two coacting pressing elements of any shape or character, and we do not desire to limit ourselves in these respects to collar molding machinery, and, when limited to collar molding machinery, we do not desire to limit ourselves to the specific details of construction or operation of the particular machine disclosed herein, as many changes may be made in the details of application and of construction of this invention without departing from the spirit of the same as set forth in the appended claims.

What we claim is:—

1. In a collar molding machine, the combination of a head having a socket, a ring for receiving the collar, the ring being movable toward and from the head for interfitting the ring with the collar thereon and the socket to mold the collar, a carriage for the ring including a cylindrical bearing, the ring having a hub journaled on and slidably axially on the bearing, a spring arranged within the bearing and having one end engaged with the carriage, said spring permitting the ring to yield relatively to the carriage when in interfitting relation with the head, means for moving the carriage and for turning the ring relatively to the head during the yielding of the spring, and a thrust bearing interposed between the hub of the ring and the other end of the spring, substantially as and for the purpose described.

2. In a collar molding machine, the combination of a head having a socket and a ring for receiving the collar, the ring being movable toward and from the head for interfitting the ring with the collar thereon and

the socket to mold the collar, a carriage for the ring including a bearing, the ring having a hub journaled on and slideable axially on the bearing, a spring interposed between the carriage and the ring for permitting the ring to yield relatively to the carriage when in interfitting relation with the head, the hub being formed with a cam slot and the bearing being formed with a pin working in the slot, substantially as and for the purpose set forth.

3. In a collar molding machine, the combination of a head having a socket, a ring for receiving the collar, the ring being movable toward and from the head for interfitting the ring with the collar thereon and the socket to mold the collar, a carriage for the ring including a bearing, the ring having a hub supported by and slideable axially of the bearing, a spindle extending axially through the bearing and the hub and having spaced apart shoulders engaging a lower face of the carriage and an upper face of the hub, a spring interposed between the carriage and the hub for permitting the ring to yield relatively to the carriage when in interfitting relation with the head, and means for moving the carriage and for turning the ring relatively to the head during the yielding of the spring, substantially as and for the purpose specified.

4. In a collar molding machine, the combination of a head having a socket, a ring for receiving the collar, the ring being movable toward and from the head for interfitting the ring with the collar thereon and the socket to mold the collar, a carriage for the ring including a bearing, the ring having a hub supported by and slideable axially of the bearing, a spindle extending axially through the bearing and the hub and having spaced apart shoulders engaging a lower face of the carriage and an upper face of the hub, the lower end of the spindle being tapered, a spring interposed between the carriage and the hub for permitting the ring to yield relatively to the carriage when in interfitting relation with the head, and a reciprocating carriage having a tapered socket for coacting with the tapered lower end of the spindle, substantially as and for the purpose set forth.

5. In a collar molding machine, the combination of a head having a socket, a ring for receiving the collar, the ring being movable toward and from the head for interfitting the ring with the collar thereon and the socket to mold the collar, a carriage for the ring including a bearing, the ring having a hub journaled on and slideable axially on the bearing, a spindle extending axially through the bearing and the hub and having spaced apart shoulders engaging a lower face of the carriage and an upper face of the hub, a spring encircling the spindle and having its

lower end bearing against an upper face of the carriage, a thrust bearing between the upper end of the spring and the hub, and means for moving the carriage, substantially as and for the purpose described.

6. In a collar molding machine, the combination of a head having a socket, a ring for receiving the collar, the ring being movable toward and from the head for interfitting the ring with the collar thereon and the socket to mold the collar, a spindle having a lengthwise slot, a carriage for the ring, said carriage being movable about the lengthwise axis of the spindle and having stop means for coacting with the lengthwise groove of the spindle when the ring is in axial alignment with the head, and means for moving the carriage lengthwise of the spindle, substantially as and for the purpose specified.

7. In a collar molding machine, the combination of a head having a socket, a ring for receiving the collar, the ring being movable toward and from the head for interfitting the ring with the collar thereon and the socket to mold the collar, a spindle having a lengthwise slot, a carriage for the ring, said carriage being movable about the lengthwise axis of the spindle and having means comprising a spring-pressed ball for coacting with the lengthwise groove of the spindle when the ring is in axial alignment with the head, and means for moving the carriage lengthwise of the spindle, substantially as and for the purpose set forth.

8. In a collar molding machine, the combination of a head having a socket, a ring for receiving the collar, the ring being movable toward and from the head for interfitting the ring with the collar thereon and the socket to mold the collar, a rotatable carriage for the ring including a bearing eccentric of the axis of the carriage, the ring having a hub supported by and slideable axially of the bearing, a spindle extending axially through the bearing and the hub and having means engaging the carriage and the hub, a spring between the carriage and the hub, and means for raising the carriage and the ring, said means having spaced apart surfaces for coacting respectively with the carriage in proximity to its axis and with the spindle, substantially as and for the purpose described.

9. In a collar molding machine, the combination of two elements, one a head having a socket and the other a ring for receiving the collar, the head being movable toward and from the ring for interfitting the ring with the collar thereon and the socket to mold the collar, means for rotating one of said elements when the same have been brought into interfitting relation, a grip for engaging the collar to hold the same from slipping during the turning of the rotative element, a carriage for moving one element

toward and from the other, and means provided on the carriage for operating the grip, substantially as and for the purpose described.

5 10. In a collar molding machine, the combination of two elements, one a head having a socket and the other a ring for receiving the collar, one of said elements being movable toward and from the other for interfitting the ring with the collar thereon and the socket to mold the collar, and the ring having a rotative movement after said elements have been brought into interfitting relation, a carriage for the ring, a compression spring interposed between the carriage and the ring for yielding after the ring has been brought into interfitting relation with the head, a collar grip carried by the ring, and means on the carriage for operating the grip to engage the collar during the compression of the spring, substantially as and for the purpose specified.

11. In a collar molding machine, the combination of a head having a socket, a ring for receiving the collar, a support for the ring, a carriage for the ring support, the carriage being movable about an axis for carrying the ring into and out of registration with the head, a guide for the carriage, the carriage having a bearing slidable and rotatable on the guide, a reciprocating carriage provided with means for engaging the bearing of the former carriage and also coacting with the former carriage at substantially the axis of the ring, substantially as and for the purpose described.

12. In a collar molding machine, a shaft, a collar shaping head carried by said shaft, a collar support, a main carriage for the collar support, the carriage being slidable on said shaft and rotatable about the shaft for carrying the collar support into and out of registration with the head, a supplementary carriage adapted to apply pressure to the main carriage adjacent the axis of said main carriage and beneath the collar support to slide the main carriage along said shaft and bring the collar support into pressing coaction with the shaping head.

13. In a collar ironing machine, a collar shaping element and a collar supporting element, a frame provided with a hub, one of said elements having a hub telescoping with the hub of the frame, a spring within said hubs for yieldingly supporting the element, said telescoping hubs provided respectively with a coacting cam slot and pin for giving a rotary oscillating movement to the element carried by said frame.

14. In a collar ironing machine, a collar shaping element and a collar supporting element, a frame provided with a hub, one of said elements having a hub telescoping with the hub of the frame, a spring within said hubs for yieldingly supporting the element,

one of said hubs provided with a slot inclined to the axis of the hub and the other hub provided with a pin movable in said slot for giving a rotary movement to the element carried by the frame.

15. In a collar molding and edging machine, the combination of a coacting shaping head and collar support with a pair of substantially parallel shafts carrying one of said elements, a main carriage rotatably mounted upon one of said shafts, the other of said elements eccentrically positioned upon said main carriage and adapted to be moved into and out of registration with the coacting element upon rotation of said carriage, and a supplemental carriage adapted to contact with the first-named carriage at two spaced points for moving the element carried thereby into pressing engagement with the coacting element.

16. In a collar molding and edging machine, the combination of a coacting shaping head and collar support with a pair of substantially parallel shafts carrying one of said elements, a main carriage rotatably mounted upon one of said shafts, the other of said elements eccentrically positioned upon said main carriage and adapted to be moved into and out of registration with the coacting element upon rotation of said carriage, and a supplemental carriage adapted to apply pressure to the main carriage simultaneously at a point adjacent the axis of said main carriage and at a point beneath the collar support.

17. In a collar molding and edging machine, the combination of a coacting shaping head and collar support with a pair of substantially parallel shafts carrying one of said elements, a main carriage rotatably mounted upon one of said shafts, the other of said elements eccentrically positioned upon said main carriage and adapted to be moved into and out of registration with the coacting element upon rotation of said carriage, and a supplemental carriage having its opposite ends mounted on and slidable longitudinally of said shafts, said supplemental carriage in its movement longitudinally of said shafts adapted to apply pressure to said main carriage at a point adjacent the axis of said main carriage and at a point beneath the collar support.

18. In a collar molding and edging machine, the combination of a coacting shaping head and collar support with a pair of substantially parallel shafts carrying said shaping head, a carriage rotatably mounted on one of said shafts and carrying said collar support, a supplemental carriage having its opposite ends mounted on and slidable longitudinally of said shafts, said supplemental carriage in its movement longitudinally of said shafts adapted to apply pressure to said main carriage at two spaced points.

19. In a collar molding and edging machine, the combination of a coacting shaping head and collar support with a pair of substantially parallel shafts carrying said shaping head, a carriage rotatably mounted on one of said shafts and carrying said collar support, a supplemental carriage having its opposite ends mounted on and slidably longitudinally of said shafts, said supplemental carriage in its movement longitudinally of said shafts adapted to apply pressure to said main carriage axially of said main carriage and beneath the collar support.
20. In a collar molding and edging machine, the combination of a coacting shaping head and collar support with a pair of substantially parallel shafts carrying said shaping head, a carriage rotatably mounted on one of said shafts and carrying said collar support, a supplemental carriage having its opposite ends mounted on and slidably longitudinally of said shafts, said supplemental carriage in its movement longitudinally of said shafts adapted to apply pressure to said main carriage axially of said main carriage and beneath the collar support, and means for moving the supplemental carriage.
21. In an ironing machine, a base, a pair of substantially vertical parallel shafts mounted on the base, a cross member carried by said shafts at their upper ends, said cross member embodying a press-head, a carriage rotatably mounted upon one of said shafts and having substantially diametrically disposed article supports adapted to be alternately brought into registration with the press-head upon the rotation of said carriage about said shaft, and means for raising the carriage vertically along the shaft to bring an article support into pressure coaction with the press-head.
22. In an ironing machine, a base, a pair of shafts carried by the base, a cross member supported by the upper ends of said shafts, said cross member embodying a press-head disposed between the shafts, a carriage rotatably mounted upon one of said shafts; an article support eccentrically mounted on the carriage and adapted upon rotation of said carriage to be moved into and out of registration with the press-head, and means for moving the carriage vertically along the shaft upon which it is mounted to bring the article support into pressing coaction with the press-head.

In testimony whereof, we have hereunto signed our names in the presence of two attesting witnesses, at Syracuse, the county of Onondaga, in the State of New York, this 28th day of March, 1914.
